Ivan E. Konigsberg

UNITED STATES PATENT OFFICE.

LEWIS E. MORRISON, OF NEWARK, NEW JERSEY, ASSIGNEE TO KLYMAX FEEDER COMPANY, A CORPORATION OF NEW JERSEY.

SHEET-HOLDING DEVICE FOR PRINTING PRESSES.

Application filed June 5, 1924. Serial No. 717,957.

To all whom it may concern:

Be it known that I, LEWIS E. MORRISON, a citizen of the United States, and resident of Newark, in the county of Essex and State 5 of New Jersey, have invented certain new and useful Improvements in Sheet-Holding Devices for Printing Presses, of which the following is a specification.

This invention relates to sheet holding 10 devices for use on platen printing presses and printing machines.

The object of the invention is to provide a device or mechanism adapted to be attached to the front edge of a platen for the 15 purpose of holding down or gripping the printed sheet and prevent curling or buckling thereof and thereby facilitate and make certain that the sheet will be seized by the delivery gripper and delivered.

20 As is well known, in a platen printing press, such for instance as the Chandler & Price type of press, the sheet is held by frisket fingers or gripper secured to the rear edge of the platen for holding the sheet 25 during the impression. Prior to the delivery or removal of the printed sheet, said frisket fingers are raised away from the printed sheet, so that it may be removed by hand or automatic delivery means.

30 With certain kinds of papers or matter to be printed, it has been found, that after the frisket fingers have been raised away from the printed sheet, the delivery edge of the sheet curls or buckles upward from 35 the platen making mechanical or pneumatic delivery, as the case may be, very difficult, if not all together impossible.

The object of this invention is therefore 40 to provide a mechanism for insuring that the delivery edge of the paper remains down on the platen in position to be seized by the delivery means.

45 For purposes of illustration and a ready understanding of this invention, it is disclosed as applied to a Chandler & Price press equipped with automatic feed and delivery means of the type shown in my U. S. Patents Nos. 1393036 and 1394183 respectively, to which patents I refer for details 50 as to the said mechanisms.

In speaking of the front and rear edges of the platen or other parts, I use these terms for explanatory purposes only and

with respect to the position of the operator of the press when hand feeding and delivering. 55

Referring to the accompanying drawings—

Fig. 1 is a plan view of a portion of the platen showing it equipped with my improved sheet holding device. 60

Fig. 2 is a view thereof looking in the direction of arrow 2 in Figure 1.

Fig. 3 is a side view looking in the direction of arrow 3 in Figure 1. 65

Fig. 4 is a diagrammatic view of a portion of a platen press illustrating the operation of my device during the impression.

Fig. 5 is a similar view showing the parts in position just prior to delivery. 70

Figs. 6 and 7 are detail views.

Referring first to Figures 4 and 5 the press is identified by the oscillating platen 10, the form member 11 and the frame 12. The paper 13 to be printed rests on a suitable auxiliary frame 14 to which is pivoted a feeding mechanism 15 which is lowered as in Figure 5 to feed or transfer the unprinted sheet to the platen and which at other times is raised out of the way as in Figure 4. The aforesaid Patent No. 1393036 discloses the feeding mechanism and I refer thereto for detailed description. 75

80 After the sheet has been printed, it is removed from the platen by a delivery gripper 16, see Figure 5, and I refer to the aforesaid Patent No. 1394183 with respect thereto.

Referring now to the other figures of the 90 drawings, there is provided two sheet holding fingers 17 and 18 of very thin suitable material. Each finger has a sheet holding portion or tongue 19 and a stem portion 20. The sheet holding portion is preferably bent as at 21 to make it resilient or springy in action. The holding fingers are further shaped at an angle to the stem as at 22 to cause said fingers to extend at an angle towards the printed sheet 23. 95

The fingers 17 and 18 are each mounted 100 as follows: Underneath the rear corners of the platen 10 there are secured two brackets 24 and 25 forming bearings 26 in which is journaled a finger shaft 27. Adjustably mounted on said shaft by means 105 of wing bolts 28 are two finger levers 29,

29. The upper ends of said levers are split as at 30, 30 and formed with a dovetailed slot as at 31, 31.

The stems 20 of the sheet holding fingers are pushed into the said slots as shown, and are thereafter firmly clamped in position by means of set screws 32, 32. It is clear, therefore, that the fingers 17, 18 are adjustably held in the finger levers and these latter may be adjusted axially on the shaft 27.

The split portions 30, dovetails 31 and set screws 32 constitute clamping means for the fingers 17, 18.

15 Means are provided for oscillating the finger shaft 27 to raise and lower the sheet holding fingers away from and down on the printed sheet and platen. To this end there is secured to the finger shaft an arm 33 20 to which is pivoted at 34 an operating lever in the form of a thin rod 35. The other, lower, end of said rod passes through a short arm 36 pivoted at 37 to the press frame 12 or other fixed part of the machine.

25 The arm 36 is preferably made of two parts of fiber 38, 38, held together by a spring 39 so as to frictionally, yet slidably, grip the rod 35 which passes through a bearing cut out 40 in said parts.

30 To the other end of the finger shaft 27 there is secured a stop arm 41 having a stop 42 adapted to engage the edge 43 of the bracket 24, see Fig. 3, to limit the movement of the finger shaft and fingers in a 35 direction away from the platen. The movement towards the platen is limited by the contact of the levers 29 against the platen itself.

35 The operation is as follows: When the platen moves from open to closed or impression position as shown in Figure 4, the rod 35 is of course drawn upward through the frictional bearing 40 in arm 36. The grip of the latter on the rod 35 presents a 45 resistance to the said movement, sufficient to cause the sheet holding fingers to be held away from the sheet and the platen during nearly all of the closing movement of the platen and during the impression. 50 During this part of the operation, the stop 42 is against the bracket 24 and the fingers lifted as shown in Figure 4.

55 During the larger first half of the opening movement of the platen the same condition prevails because only a relatively small portion of the rod 35 is being forced through the bearing 40 and during this first part of the opening movement, the arm 36 rocks forward and offers very little resistance to the passage of the rod 35.

60 This resistance, however, becomes greater as the platen moves upward and the parts are so arranged, that immediately prior to the moment when the usual frisket fingers 65 or platen grippers 50 let go of the sheet,

the angular relation between the rod 35 and the arm 36 prevents further rocking movement of the latter, the resistance of the bearing 40 therefore comes into full play and the shaft 27 is rocked to cause the 70 fingers 17-18 to close down on the delivery edge of the sheet. Further upward movement of the platen of course causes the rod 35 to be pushed down through the arm 36, 75 because of the greater force applied. 75

In other words, just before the frisket fingers 50 let go of the sheet, the sheet is gripped by the sheet holding fingers and curling or buckling of the sheet is prevented. And as seen in Figure 5, the sheet holding 80 fingers remain down on the sheet when the platen is in full open position, thus holding the sheet in proper flat position to be seized by the delivery gripper 16, this being possible because only the corners of the sheet 85 are held down.

On the closing of the platen, the sheet holding fingers remain down on the sheet long enough to permit the delivery grippers to close thereon. When this happens the friction at 40 comes into effect to raise the fingers from the sheet to permit the delivery grippers to remove the same, and when the fingers are raised, they are at the same time moved forward with respect to the 90 platen because of the position of the pivot at 27 so that said fingers are out of the way of the fresh sheet which at this time is being fed to the platen.

To recapitulate: Because of the swinging 100 or rocking arm 36, the fingers will be down on the sheet during the time required for said arm to swing and this period is utilized to permit the fingers to hold the sheet for delivery purposes and thus accomplish the 105 object of the invention. At all other times, the sheet holding fingers are raised from the platen because of the force with which the operating lever 35 is gripped by the 110 frictional bearing at 40.

115 The foregoing is thought to fully explain this invention, which may be used with equal advantage for both manual and mechanical or pneumatic delivery as the case may be. The sheet holding fingers prevent the sheet from curling or moving on the platen and this facilitates the removal of the sheet by the operator when delivering by hand. The term sheet herein is to be understood to cover all matter to be printed, and the term delivery edge is intended as meeting the edge of the sheet which is seized in removing it from the platen. While I have shown my invention in its preferred form, it will be further understood that I do not 120 wish to limit myself to the precise details disclosed, but that changes and alterations may be made within the principle of the invention without departing from the scope 125 of the appended claims. 130

I claim:—

1. The combination with a press including a platen having a cycle of movement from a sheet receiving position to a printing position, of sheet holding resilient fingers pivoted on said platen for momentarily holding the delivery edge of the printed sheet against the platen while the latter is in its sheet receiving position and means for operating said fingers.
2. The combination with a press including a platen having a cycle of movement from a sheet receiving position to a printing position, of means secured to said platen for momentarily holding the delivery edge of the printed sheet against the platen while the latter is in its sheet receiving position and devices for operating said holding means.
3. The combination with a press including a platen having a cycle of movement from a sheet receiving position to a printing position of means secured to the said platen for holding down against it the corners of the delivery edge of the printed sheet while the

platen is moving into sheet receiving position and devices for operating said holding means.

4. The combination of a platen, means for printing a sheet thereon, fingers pivoted to the platen and adapted to engage the corners of the delivery edge of the sheet to prevent the latter from curling on the platen and means for operating said fingers to engage the sheet as aforesaid prior to the delivery of said sheet.

5. The combination of a platen, members pivoted thereto and adapted to engage the delivery edge of the printed sheet and mechanism for operating said fingers into engagement with the sheet after it has been printed and prior to the delivery of said printed sheet.

6. The combination of a platen, members pivoted thereto and adapted to engage the delivery edge of the printed sheet and means pivoted to said press and frictionally connected to the said members.

LEWIS E. MORRISON.
